UNITED STATES PATENT OFFICE.

MORRIS A. HEIMANN, OF ST. LOUIS, MISSOURI.

DESIGN FOR A TROUSERS-HANGER.

SPECIFICATION forming part of Design No. 33,294, dated October 2, 1900.

Application filed June 28, 1900. Serial No. 22,002. Term of patent 7 years.

To all whom it may concern:

Be it known that I, MORRIS A. HEIMANN, a citizen of the United States, residing at St. Louis, in the State of Missouri, have invented and produced a new and original Design for a Trousers-Hanger, of which the following is a specification, reference being had therein to the accompanying drawings.

This invention relates to a new and original design for a trousers-hanger, of which the following is a specification.

Figure 1 is a perspective view of my invention, showing its complete design. Fig. 2 is a top plan view of the same.

As shown in the drawings, the leading or material feature of my design consists of two horizontal parallel bars 1, each being bent outwardly at their center portion, forming be-

tween them an elongated slot 2, the inner surfaces of the ends being arranged in contact. 20 Extending upwardly from each bar at the center is a single strand of wire 3, arranged on a slant and bent across in opposite directions and again bent at 4, extending upwardly and terminating into a loop 5. 25

Having described my invention, what I claim as new, and desire to secure by Letters Patent, is—

The design for a trousers-hanger as herein shown and described. 30

In testimony whereof I affix my signature in presence of two witnesses.

MORRIS A. HEIMANN.

Witnesses:

L. HIMANN,
FRED CARLEY.
